(57) **CLAIM**

The ornamental design for a robot pilothead controller, as shown and described.

DESCRIPTION

FIG. 1 is a front view of a robot pilothead controller of the present invention;

FIG. 2 is a rear view of the robot pilothead controller shown in FIG. 1;

FIG. 3 is a right side view of the robot pilothead controller shown in FIG. 1;

FIG. 4 is a left side view of the robot pilothead controller shown in FIG. 1;

FIG. 5 is a top view of the robot pilothead controller shown in FIG. 1;

FIG. 6 is a bottom view of the robot pilothead controller shown in FIG. 1; and,

FIG. 7 is a left side perspective view of the robot pilothead controller shown in FIG. 1.

1 Claim, 7 Drawing Sheets
